(57) **CLAIM**

The ornamental design for a throw wrap, as shown and described.

DESCRIPTION

FIG. 1 is a front view of a throw wrap showing our new design;

FIG. 2 is a back view thereof;

FIG. 3 is a top view thereof;

FIG. 4 is a bottom view thereof;

FIG. 5 is a right side view with the opposite side being a mirror image;

FIG. 6 is a top right front perspective view thereof; and,

FIG. 7 is a bottom right side back perspective view thereof. The broken lines and the area within the broken lines form no part of the claimed invention.
